UNITED STATES PATENT OFFICE.

PHILIP S. MINGES, OF CHARLESTON, SOUTH CAROLINA.

COMPOUND TOOL.

1,369,829.

Specification of Letters Patent.

Patented Mar. 1, 1921.

Application filed December 24, 1918, Serial No. 347,140.

To all whom it may concern:

Be it known that I, PHILIP S. MINGES, a citizen of the United States, residing at Charleston, in the county of Charleston and 5 State of South Carolina, have invented certain new and useful Improvements in Compound Tools, of which the following is a specification.

This invention relates to compound tools 10 of the wrench type, and has for its object to provide a tool particularly serviceable for work on bicycles and similar machines containing a plurality of nuts of different sizes, the tool including a set of wrenches 15 of the socket and fixed jaw types as well as a hammer and a screw driver. The tool includes a handle or stock provided at each end with wrenches of the socket type and of different sizes, and also provided with a set 20 of fixed jaw end wrenches of different sizes. One end of the stock is provided with a screw-driver and the other end with a hammer head.

The tool is illustrated in the accompanying 25 drawings, in which Figure 1 is a plan thereof, and Fig. 2 is an edge view.

Referring specifically to the drawings, 6 indicates the stock or handle, which is slotted lengthwise as shown at 7. One end of the 30 handle or stock is enlarged to form a head 8, and the other end enlarged to form a head 9. In each of these heads sockets of different sizes are formed. On one side the head 8 has a socket 10 and on the other side a larger 35 socket indicated at 11. And on one side the head 9 has a socket 12 and on the other side a larger socket 13. This makes four sockets in all, of different sizes, which will take dif-

ferent size nuts by being placed thereover. The sockets extend through the heads, being 40 stepped where they join, to produce different sizes on the opposite sides. The head 8 is also provided on one edge with a hammer face 14 and on the opposite side with a pair of parallel jaws 15 which may be used as a 45 wrench or the like.

A plurality of fixed jaw end wrenches indicated at 16 are pivoted at 17 to swing into and out of the slot 7. These wrenches consist of relatively thin metal plates with fixed 50 jaws at the free ends of different sizes. The head 9 also has a screw driver 18 projecting from the end thereof.

The whole tool provides a set of wrenches and other instruments in very small and convenient compass, and will be found very serviceable for bicycle and automobile work, although of course capable for use on work of other kinds.

I claim:

A compound tool comprising a handle having wrench heads at opposite ends, the handle being slotted between the heads, and a plurality of fixed-jaw wrenches pivoted at one end to the handle within the slot, the 65 length of said fixed-jaw wrenches being less than that of the slot, whereby they may all be folded into the slot in parallelism to the handle.

In testimony whereof, I hereby affix my 70 signature in presence of two witnesses.

PHILIP S. MINGES.

Witnesses:

EUGENE G. JOHNSON,
W. K. McDOWELL.
